UNITED STATES PATENT OFFICE.

TALMA T. GREENWOOD, OF EAST TEMPLETON, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

METHOD AND APPARATUS FOR PREVENTING EXPLOSIONS IN ELECTRICAL APPARATUS.

Application filed April 29, 1924. Serial No. 709,874.

This invention relates to electric switches wherein the circuit-interrupting arc is drawn in an arc-quenching fluid capable of forming gases and vapors which are explosive when 5 mixed in suitable proportions with air; or other electrical apparatus containing a vaporizable combustible fluid; and has for its object a method and apparatus for maintaining so great a proportion of the gases 10 and vapors of the arc-quenching or insulating fluid with air that the mixture cannot explode.

The idea of maintaining the combustible content of the gaseous mixture too rich for 15 the mixture to explode is also disclosed in my co-pending application Serial No. 675,949, filed November 20, 1923.

The figure represents diagrammatically an 20 electric switch embodying the invention.

As here shown the electric switch includes 25 a casing 10 which may or may not be completely air tight. Said casing is adapted to contain the arc-quenching fluid, as oil, to some level 11, whereby to provide an expansion 30 space 12 above the fluid level. Stationary switch members 13 extend into the oil and a bridging member 14 cooperates with said stationary switch members to control the current through the switch. The circuit-interrupting arc is drawn between the 35 bridging member and the stationary switch members.

Ordinarily fluid vapors and gases collect 40 in the expansion space 12 and mix with the air contained therein to form an explosive mixture.

In accordance with this invention I provide 45 a method and means for maintaining the mixture in the gas expansion space so rich in fluid vapors and gases that it can not explode. To this end I may arrange a conduit 50 in communication, at 16, with the fluid in the switch below the fluid level, and, at 17, with the expansion space 12 above the fluid level, whereby fluid may stand in said conduit to the same level as in the switch casing. An electric heating element 18 is arranged in said conduit 15, mainly below the fluid level. Said heating element may be supplied with current from any suitable 55 source as the current transformer 19 disposed in inductive relation to a stationary switch member 13. Said heating element 18

is adapted to boil the fluid in the conduit 15 and generate fluid vapor which is adapted 55 approximately completely to fill the expansion space 12 and displace the air contained therein, which air may escape from the switch through suitable leakage paths or through the loaded check valve 20. Preferably 60 fluid vapor is generated continually or while current is passing through the switch and the pressure of the fluid vapor in the expansion space is preferably about or slightly in excess of atmospheric pressure, 65 whereby to prevent entrance of atmospheric air. The capacity of the heating element 18 may be such as to maintain the pre-determined pressure regardless of the condensing effect of the cool walls of the switch casing. 70

Excess vapor pressure, as that generated 75 upon circuit interruption may be relieved by the loaded check valve 20, which valve, preferably, is arranged to close when the pressure within the switch is approximately that of the atmosphere.

A fluid gage 22 may serve to indicate the 80 fluid level within the casing and fluid may be added to the casing through said gage to compensate for fluid lost through vapor leakage.

By generating fluid vapor independently 85 of the main body of fluid in the casing, the main body of fluid is maintained approximately at its normal operating temperature and, consequently, the performance of the 90 switch or other electrical apparatus is not impaired.

The construction may be otherwise modified without departing from the spirit of 95 the invention.

I claim:

1. The method of preventing explosions 100 in the casings, of electrical apparatus containing a fluid, the vapor of which is explosive when mixed with air, which method consists in generating vapor from the fluid in such quantities as to maintain the fluid vapor in the casing in such a large proportion of the total mixture content of the casing that the mixture cannot explode.

2. The method of preventing explosions 105 in the casings of electrical apparatus containing a fluid, the vapor of which is explosive when mixed with air, which method consists in heating a portion of the fluid

and generating vapor from the heated fluid in such quantities as to maintain the fluid vapor in the casing in such a large proportion of the total mixture content of the casing that the mixture cannot explode.

3. The method of preventing explosions in the casings of electrical apparatus containing a fluid, the vapor of which is explosive when mixed with air, which method consists in heating a portion of the fluid out of heat-transmitting relation with the main body of fluid and generating vapor from the heated fluid in such quantities as to maintain the fluid vapor in the casing in such a large proportion of the total mixture content of the casing that the mixture cannot explode.

4. The combination of an enclosing casing containing a vaporizable fluid, the vapor of which is explosive when mixed with air in suitable proportions, and an expansion space above the fluid adapted to contain air, electrical apparatus contained in the fluid, and means to generate vapor of the fluid to fill the expansion space to an extent to exclude deleterious quantities of air.

5. The combination of an enclosing casing containing a vaporized fluid, the vapor of which is explosive when mixed with air in suitable proportions, and an expansion space above the fluid adapted to contain air, and means to heat the fluid locally and generate vapor of the fluid to occupy the expansion space in a proportion so great that it is not explosive with the air therein.

6. The combination of an enclosing casing containing a vaporized fluid, the vapor of which is explosive when mixed with air in suitable proportions, and an expansion space above the fluid adapted to contain air, electrical apparatus contained in the fluid, and means to heat the fluid locally and generate vapor of the fluid to occupy substantially the entire volume of the expansion space and exclude other vapors or gases.

7. The combination of an enclosing casing containing a vaporizable fluid, the vapor of which is explosive when mixed with air in suitable proportions, and an expansion space above the fluid adapted to contain air, electrical apparatus contained in the fluid, means to heat a portion of the fluid external of the casing and generate vapor, and means to conduct the fluid vapor into the casing.

8. The combination of an enclosing casing containing a vaporizable fluid, the vapor of which is explosive when mixed with air in suitable proportions, and an expansion space above the fluid adapted to contain air, electrical apparatus contained in the fluid, and means to heat a portion of the fluid free from heat-imparting relation with the fluid body, and liberate the vapor into the expansion space.

9. The combination of an enclosing casing

containing a vaporized fluid, the vapor of which is explosive when mixed with air in suitable proportions, and an expansion space above the fluid adapted to contain air, electrical apparatus contained in the fluid, and means to heat a portion of the fluid by the current traversing said electrical apparatus and liberate the vapor into the expansion space.

10. The combination of an enclosing casing containing a vaporizable fluid, the vapor of which is explosive when mixed with air in suitable proportions, and in expansion space above the fluid adapted to contain air, electrical apparatus contained in the fluid, a conduit disposed externally of the casing and having a fluid inlet in communication with the casing below the fluid level therein and having a vapor outlet in communication with the expansion space of the casing, and means to vaporize the fluid in said conduit.

11. The combination of an enclosing casing containing a vaporizing fluid, the vapor of which is explosive when mixed with air in suitable proportions, and an expansion space above the fluid adapted to contain air, electrical apparatus contained in the fluid, a conduit disposed externally of the casing and having a fluid inlet in communication with the casing below the fluid level therein and having a vapor outlet in communication with the expansion space of the casing, and a continually-operative electrical heating element arranged to vaporize the fluid in said conduit.

12. An electric switch comprising an enclosing casing adapted to contain a vaporizable arc-quenching fluid and an expansion space above the fluid, stationary and movable switch members immersed in the fluid, an external conduit having a fluid inlet in communication with the interior of the casing below the fluid level therein and having a vapor outlet in communication with the expansion space of the casing, and means to vaporize the fluid in said conduit.

13. An electric switch comprising an enclosing casing adapted to contain a vaporizable arc-quenching fluid and an expansion space above the fluid, stationary and movable switch members immersed in the fluid, an external conduit having a fluid inlet in communication with the interior of the casing below the fluid level therein and having a vapor outlet in communication with the expansion space of the casing, and means to maintain vapor of the fluid in said expansion space including an electrical heating element arranged to vaporize the fluid in said conduit.

14. An electric switch comprising an enclosing casing adapted to contain a vaporizable arc-quenching fluid and an expansion space above the fluid, stationary and movable switch members immersed in the fluid, an

- external conduit having a fluid inlet in communication with the interior of the casing below the fluid level therein and having a vapor outlet in communication with the expansion space of the casing, and means to maintain vapor of the fluid in said expansion space including an electrical heating element arranged to vaporize the fluid in said conduit, and a current transformer arranged in inductive relation with a switch member and connected with said electrical heating element.
15. An electric switch comprising an enclosing casing adapted to contain a vaporizable arc-quenching fluid and an expansion space above the fluid, stationary and movable switch members immersed in the fluid, an external conduit having a fluid inlet in communication with the interior of the casing below the fluid level therein and having a vapor outlet in communication with the expansion space of the casing, and means to maintain vapor of the fluid in said expansion space including an electrical heating element arranged to vaporize the fluid in said conduit, and a current transformer arranged in inductive relation with a switch member and connected with said electrical heating element.
16. The combination of a fluid containing receptacle, electrical apparatus contained in the receptacle, a conduit disposed externally of the receptacle having upper and lower openings both arranged in communication with the interior of said receptacle respectively above and below the fluid level therein, and an electrical heating apparatus arranged in thermal relation with said conduit.
17. In testimony whereof, I have signed my name to this specification.
- TALMA T. GREENWOOD.
